UNITED STATES PATENT OFFICE

123,856

DESIGN FOR A COMBINED SPLASH GUARD AND SIGNAL DEVICE FOR BICYCLES

Clem Clark, Fairfield, Ala.

Application September 4, 1940, Serial No. 94,809

Term of patent 7 years

To all whom it may concern:

Be it known that I, Clem Clark, a citizen of the United States of America, residing at Fairfield, in the county of Jefferson and State of Alabama, have invented a new, original, and ornamental Design for a Combined Splash Guard and Signal Device for Bicycles, for which the following is a specification, reference being had to the accompanying drawing, forming a part thereof.

In the drawing:

Figure 1 is a front elevational view of a com-

bined bicycle splash guard and signal device showing my new design,

Figure 2 is a side view thereof, and

Figure 3 is a rear view of the same.

The dominant features of my design are shown in full lines in the drawing.

I claim:

The ornamental design for a combined splash guard and signal device for bicycles, as shown and described.

CLEM CLARK.
